EXERCISING APPARATUS

Filed Jan. 14, 1928

Inventor:
James C. Baine,
By *Dympfle, Chittom & Miles,*
Atty's.

UNITED STATES PATENT OFFICE

JAMES C. BAINE, OF MICHIGAN CITY, INDIANA

EXERCISING APPARATUS

Application filed January 14, 1928. Serial No. 246,816.

My invention relates to stationary exercising apparatus patterned after the common form of bicycle, permitting the person using the apparatus to exercise the same muscles as in the case of riding a bicycle.

One of my objects is to provide in connection with the exercising apparatus, and observable to the one exercising thereon, indicating means which preferably indicate not only the speed at which the rider would be traveling if the apparatus were a bicycle, but also the mileage which he would cover.

Another object is to provide a neat, attractive, and economical construction of exercising apparatus of the general character above referred to, and other objects as will be manifest from the following description.

Referring to the accompanying drawings: Figure 1 is a view in side elevation of my improved exercising device. Figure 2 is an enlarged broken section taken at the line 2 on Fig. 1 and viewed in the direction of the arrow; and Figure 3, an enlarged sectional view taken at the line 3 on Fig. 1 and viewed in the direction of the arrow.

The construction illustrated comprises a base member 4 adapted to be rigidly secured to a floor or the like as by means of the fastening devices 5, this base member forming a support for the various parts of the apparatus.

Rigidly secured to and rising from the base plate 4 is a series of uprights 6, 7 and 8, each preferably of tubular form and connected together by tubular cross rods 9 and 10. Mounted in the upright 6 to be adjustable up and down therein is a seat post 11 carrying a seat 12 for the one using the apparatus; and mounted in the upright 8 is a handle bar 40 post 13 to which a handle bar 14, such as is provided on bicycles, is secured. Mounted in the upright 7 is a post 15 terminating in a crank-hanger bearing 16 in which a pedal-equipped crank-hanger 17 connected with a sprocket 18, is journaled. The arrangement of the seat 12, crank-hanger 17, and handle bar 14 is similar to that provided in the ordinary bicycle.

The apparatus also comprises a forked frame member 19 rigidly connected at its

lower end to the base 4 and at its other end to the upright 8, this fork member being similar to the rear fork member commonly provided in bicycle constructions and forming a support for a wheel 20 rotatably supported on an axle 21 rigidly secured at its ends in the opposite side members 22 of the frame 19. The wheel 20 is provided with a sprocket 23 connected with the sprocket 18 by a sprocket chain 24.

Means are associated with the wheel 20 for producing, if desired, resistance to the rotation thereof, the means shown, which are preferably adjustable either to permit the wheel to freely rotate or present variable resistance to its rotation, comprising a yoke frame 25 pivotally connected at 26 to the frame 19, the frame 25 carrying a roller 27 for engagement with the periphery of the wheel 20, the degree of pressure exerted by the roller 27 against the wheel being regulated by a screw device 28 engaging at its lower end with the base 4 and having threaded connection with the yoke 25.

The wheel 20 in being rotated by the user of the apparatus, drives an indicator device which by preference is a combined mileage and speed indicator, which by way of example may be of any well known construction and is represented at 29, this indicating device, shown as having a terminal bevel pinion 30 through the medium of which it is operated, being provided with an apertured bracket arm 31 at which the device is supported, in the position shown, on the axle 21, the wheel 20 being provided with a bevel gear 32 rotating therewith and meshing with the bevel pinion 30.

It is preferred that the wheel 20 be of smaller diameter than the wheels provided on bicycles as commonly provided, in which case it is desirable that the parts of the exercising apparatus be so proportioned that indicating devices provided for use with bicycles may be used as a part of the equipment of the apparatus and substantially accurately indicate the operation thereof as in the case of the driving of an ordinary bicycle. This may be accomplished either by making the ratio between the drive sprocket and the

driven sprocket or between the drive gear on the wheel and the drive gear of the indicator, such as to produce this result.

While I have illustrated and described a particular construction involving my invention, I do not wish to be understood as intending to limit it thereto as the same may be variously modified and altered without departing from the spirit of my invention.

What I claim as new, and desire to secure by Letters Patent, is:

1. An exercising apparatus comprising a base, a seat-supporting upright and a handle-bar-supporting upright rising therefrom, an relatively low upright on said base intermediate the first and second mentioned uprights, means connecting and bracing the relatively low upright to and from the first mentioned uprights, a crank hanger journaled at the top of the third upright, a forked frame member forwardly of the second mentioned upright having one arm fastened to the second mentioned upright and the other arm fastened to the base, a wheel mounted by the forked frame member, and a driving connection between said crank hanger and said wheel.

2. An exercising apparatus comprising a base, a seat-supporting upright and a handle-bar-supporting upright rising therefrom, an upright on said base intermediate said first and second mentioned uprights, a crank hanger journaled at the top of the third upright, a forked frame member forwardly of the second mentioned upright having one arm fastened to the second mentioned upright above the third mentioned upright and having the other arm fastened to the base, a wheel mounted by the forked frame member, and a driving connection between said crank hanger and said wheel located on the side of the wheel opposite the said forked member.

3. An exercising apparatus comprising a base, a seat-supporting upright and a handle-bar-supporting upright rising therefrom, an upright on said base intermediate said first and second mentioned uprights, a crank hanger journaled at the top of the third upright, a forked frame member forwardly of the second mentioned upright having one arm fastened to the second mentioned upright above the third mentioned upright and having the other arm fastened to the base, a wheel mounted by the forked frame member, a driving connection between said crank hanger and said wheel, and means operable to apply pressure to the wheel to retard its motion, the latter means being fastened to one of the arms of the frame member and located between such arm and the second mentioned upright.

JAMES C. BAINE.
